UNITED STATES PATENT OFFICE.

CURTIS L. CRUVER AND WILLIAM A. PETERS, OF CHICAGO, ILLINOIS.

MUSICAL TOY.

1,109,903.

Specification of Letters Patent.

Patented Sept. 8, 1914.

Application filed October 8, 1913. Serial No. 794,019.

To all whom it may concern:

Be it known that we, CURTIS L. CRUVER and WILLIAM A. PETERS, both residing at Chicago, in the county of Cook and State of Illinois, citizens of the United States, have invented certain new and useful Improvements in Musical Toys; and we do hereby declare the following to be a full, clear, and exact description of the invention, such as will enable others skilled in the art to which it appertains to make and use the same.

Our invention relates to finger-actuated musical toys or noise-making novelties for imitating the sound of a snare drum or of a rattle.

The prime object of our invention is to provide a miniature and quickly assembled drum constructed of few and cheap parts, and in which a single flexible member will simultaneously maintain the parts in their assembled relation to one another and provide the power for moving the beater or tapper into rapid and forcible impact against the diaphragm or sounding membrane of the drum.

Other objects are to provide a simple construction in which the casing of the drum may be simultaneously equipped with formations for anchoring the head or sounding disk of the drum therein and with formations for preventing the edges of the casing from cutting the fingers when held in the hand, and to provide simple means for varying the pitch of the instrument.

Other objects will appear from the following specification and from the accompanying drawings, in which:

Figures —1— and —6— are elevations of musical toys embodying our invention. Fig. —2— is a vertical section through Fig. —1— along the line 2—2. Fig. —3— is a horizontal section through the drum of Fig. —1— along the line 3—3 of Fig. —2—. Fig. —4— is an enlarged fragmentary section of Fig. —2— along the line 4—4. Fig. —5— is a fragmentary view showing an alternative form of sounding disk and of the formation upon the casing for holding the said disk in position. Fig. —7— is a horizontal section through Fig. —6— along the line 7—7.

In Figs. —1—, —2—, and —3—, the toy of our invention consists of a disk 1 of metal or other resonant material equipped at its periphery with a stiffening flange 2, which flange conforms substantially in section to

the interior of a grooved formation longitudinally disposed upon a metal strip intermediate of the edges thereof. After the said groove has been formed in the strip 3, 60 the latter is rolled or wrapped around the disk 2 to form a substantially cylindrical casing 3. However, the strip is shorter than the circumference of the disk or insufficient to completely encircle the said disk, and 65 hence leaves a gap between the ends of the said strip. The metal casing 3 formed by thus curving the strip is equipped at two points with prongs 5 directed away from the ends of the strip, the prongs serving as 70 means for securing the ends of a loop of twine or other flexible material to portions 62 of the casing disposed at opposite sides of the said gap. The two strands of flexible cord 6 thus stretched across the said gap 75 are twisted about each other by means of a bar 7 of metal or wood, which bar is then slid inwardly of the casing until its inner end reaches substantially to the center of the disk 1, the length of the bar being such 80 that the other end thereof will project considerably beyond the periphery of the casing 3. It will be obvious from Figs. —1— and —3— that when the cord 6 has thus been tightly twisted in the proper direction, 85 its torsional tendency to untwist will tend to press the inner end 8 of the bar against the disk 1, while the flexibility of the cord 6 will enable the said end 8 to be raised out of engagement with the disk 1 by a downward pressure upon the outer end 9 of the said bar or beater. By rapidly sliding one or more fingers over the projecting end 9, the bar may be caused to effect a correspondingly rapid tapping of the sounding disk 95 or diaphragm of the drum, thereby giving imitations of snare drum or rattle effects. At the same time, the tension of the flexible member 6 will keep the sheet metal member 3 wrapped tightly around the disk 1, so 100 that the latter will be firmly held within the cylindrical drum casing without requiring auxiliary fastening means of any kind.

In forming the metal casing member 3, we preferably simultaneously form both the 105 aforesaid groove for receiving the edge portion of the diaphragm 1, and a groove at each of the respective edges of the said strip. When the latter is wrapped around the disk to house the same, the grooves at 110 the edges thereof will form outwardly convexed bead formations 10, thereby present-

ing rounded portions at the end of the casings so that the latter may be firmly grasped with the fingers without danger of cutting the fingers.

6. Instead of equipping the disk 1 with a circumferentially disposed stiffening flange 2, the disk may be made of heavier material without any peripheral flange, as shown in Fig. —5—, the casing being equipped with 10 a correspondingly more acute grooved formation for receiving the said disk. By compressing either end of the casing manually (as shown in dotted lines in Fig. 1), the size of the opening at that end will be varied, 15 thereby altering the pitch of the sound. In either case, it will be evident from Figs. —2— and —5— that the bore of the substantially cylindrical casing is smaller than the disk, and that the tension of the twisted 20 flexible member continually tends to decrease the diameter of the said casing, thereby causing the grooved portion of the latter to firmly grip the disk. Moreover, an auxiliary disk or member 11 may be mounted in 25 the grooved formation at one end of the drum, as shown by dotted lines in Fig. —2—. Instead of having prongs upon the casing for receiving the end loop of the flexible member, the latter may be threaded through 30 perforations 12, as shown in Fig. —6—. Likewise, various other modifications may be made in the construction herein disclosed, without departing from the spirit of our invention. For example, instead of providing 35 the casing with a groove for receiving the resonant disk to hold the latter in its normal position transverse to the axis of the cylindrical casing the disk may be equipped with a plurality of prongs 13, interfitting 40 slots or perforations in the casing, as shown in Figs. —6— and —7—. In any case, it will be obvious that the single flexible member will simultaneously hold the casing tightly wrapped around the disk and provide 45 the torsional tendency for effecting the desired tapping or noise-making movement of the tapper, while both the outer surface of the casing and the faces of the resonant disk will be exposed to view, so that these 50 surfaces may be used for the presentation of advertising matter. Also, that the gap or opening longitudinally of the cylinder between the ends of the material forming the casing may be of any desired width that 55 will permit the free movement of the tapper between the said ends.

We claim as our invention:

1. A musical toy comprising a cylinder having a longitudinally disposed opening in 60 one side thereof, a diaphragm mounted within the said cylinder transversely of the axis thereof, a torsionally flexible member stretched across the said gap and secured at its opposite ends to the said cylinder, and a 65 tapper carried by the said flexible member,

one end of the said tapper extending inward of the cylinder through the said gap and normally pressed against the said diaphragm by the torsional action of the said flexible member, the other end of said 70 tapper providing a handle for digitally manipulating the tapper.

2. A musical toy comprising a cylinder having a gap longitudinally disposed therein, a resonant disk mounted within the said cylinder, a torsionally flexible member mounted upon the said cylinder and extending across the said gap, and a tapper carried by the said flexible member, the ends of the said tapper extending respectively outward beyond the periphery of the said cylinder and inward into engagement with the said resonant disk, there being circumferentially disposed formations upon the said cylinder engaging the said disk to prevent 80 the motion of the latter longitudinally of the cylinder, the tension of the said flexible member simultaneously holding the said cylinder with its said formations in their 85 said engagement with the said disk and holding the inner end of the tapper yielding against the said disk.

3. A musical toy comprising a cylinder having a longitudinally disposed gap therein and having an inwardly concave groove 95 extending circumferentially thereof, a resonant disk housed by the cylinder and seated in the said groove, the bore of the said cylinder being smaller than the said disk, a torsionally flexible member stretched 100 across the said gap and secured at its ends to the said cylinder, and a tapper carried by the said flexible member and having one end yieldingly pressed by the flexible member against the said disk, the tension of the 105 said flexible member tending to decrease the diameter of the cylinder, whereby the said groove formation is caused to house the edges of the disk to hold the latter rigid 110 with respect to the cylinder.

4. A musical toy comprising a cylinder of resonant material having a longitudinally disposed gap therein and having a pair of prongs disposed at opposite sides of the said gap, an endless flexible member looped 115 over the said prongs and stretched across the said gap, and a tapper carried by the portion of the said flexible member opposite the said gap; the said flexible member being twisted about itself, whereby its torsional 120 tendency to untwist will hold the inner end of the said tapper in yielding engagement with the said disk, the other end of the said tapper projecting outwardly of the said cylinder and enabling the tapper to be digitally manipulated.

5. A musical toy comprising a disk of resonant material, a casing therefor formed of a strip of metal shorter in length than the circumference of the said disk and equipped 125

with a longitudinally disposed groove formation, the said strip being wrapped about the periphery of the said disk to form a casing for the latter, the edge portion of the 5 said disk being seated in the said groove to interlock the disk with the said casing, a torsionally flexible member secured at its ends to portions of the said housing and stretched across the gap between the ends 10 of the strip forming the said casing, and a tapper carried by the said flexible member and projecting through the said gap into the interior of the said housing and into engagement with the said disk, the said tapper 15 also having a portion projecting outwardly of the casing to afford a means for digitally manipulating the tapper.

6. A musical toy comprising a disk of resonant material, a casing formed of a strip 20 of metal shorter in length than the circumference of the side disk and equipped with longitudinally disposed groove formations at its lateral edges and along a line intermediate of the said edges, the said strip being wrapped about the periphery of the said 25 disk to partially incase the latter, the said intermediary groove affording a seat for the said disk, the said grooves at the edges of the disk affording a rounding of the end 30 portions of the said casing, a torsionally flexible member secured at its ends to portions of the said housing and stretched across the gap between the ends of the strip forming the said casing, and a tapper carried 35 by the said flexible member and projecting through the said gap into the interior of the said housing and interengaging with the said disk, the said tapper also having a portion projecting outwardly 40 of the casing to afford a means for digitally manipulating the tapper.

7. A musical toy comprising a casing having a longitudinally disposed opening in one

side thereof, a diaphragm mounted within the casing intermediate of the ends thereof, 45 and a tapping member mounted upon the casing and yieldingly bearing at one end against the said diaphragm; the said casing capable of being manually flexed to increase or decrease the opening at one end thereof, 50 thereby altering the pitch of the toy.

8. A musical toy comprising a disk of resonant material, a casing therefor formed of a strip of metal shorter in length than the circumference of the said disk, the said strip 55 being wrapped around the periphery of the said disk to partially incase the latter, a torsionally flexible member secured at its ends to the said casing and stretched across the gap between the ends of the strip forming 60 the said casing, and a tapper carried by the said flexible member and projecting through the said gap into the interior of the said casing and into engagement with the said disk, the opening between the ends of 65 the said strip permitting the latter to be flexed to enlarge or contract the opening at one end of the said casing to vary the pitch of the toy.

9. In a musical toy having a resonant 70 disk and a tapper supported in proximity thereto and yieldingly impinging thereagainst, a member wrapped around the disk to form a casing open at one end; the said member being manually flexible to increase 75 or decrease the size of the said opening, thereby varying the pitch of the toy.

In testimony whereof we have signed our names in the presence of two subscribing witnesses.
